Silas M. Ford

UNITED STATES PATENT OFFICE.

SILAS M. FORD, OF ST. PAUL, MINNESOTA.

ROOFING ELEMENT.

1,424,459.

Specification of Letters Patent.

Patented Aug. 1, 1922.

Application filed November 26, 1919. Serial No. 340,794.

To all whom it may concern:

Be it known that I, SILAS M. FORD, a citizen of the United States, and resident of St. Paul, county of Ramsey, and State of Minnesota, have invented certain new and useful Improvements in Roofing Elements, of which the following is a specification, and which are illustrated in the accompanying drawings, forming a part thereof.

10 The invention relates to prepared roofing elements and is an improvement upon the invention described and claimed in Patent No. 1,207,523, issued to me December 5, 1916. The object of the invention is the provision 15 of roofing elements designed to afford an efficient roof covering of improved appearance and great durability.

While it has been a common practice to cut prepared roofing into separate shingles 20 and short strips comprising a plurality of connected shingles, difficulty is experienced in the use of these materials upon a roof for the reason that the exposed portions of the shingles or shingle strips may be raised 25 by the wind and thereafter present an unsightly appearance and an inefficient roof covering. Furthermore, prepared roofing shingles and shingle strips, as ordinarily constructed, are of less thickness than is 30 generally regarded as desirable for the purpose of producing a satisfactory appearance when laid in overlapping rows.

The present invention accordingly contemplates prepared roofing shingles and shingle strips having the weather portions stiffened 35 with a marginal reinforcement which adds to the relief of the shingle when in use and effectively resists lifting of the free edges of the shingles whether by the wind or other 40 causes.

In the accompanying drawings:—

Fig. 1 is a perspective view of a prepared roofing shingle embodying the features of improvement provided by the invention;

15 Fig. 2 is an end view of the same;

Fig. 3 is similar to Fig. 1, but illustrates the employment of the invention in a strip shingle and is partly broken away to expose the intermediate and body layer of the prepared roofing material;

Fig. 4 is an edge view of the strip shingle illustrated in Fig. 3; and

Fig. 5 is a detail sectional view taken on the line 5—5 of Fig. 3.

5 In carrying out the invention, the weather portion 13 of an individual shingle, as 10

(Fig. 1) or the shingle tabs 12 of a strip shingle, as 11 (Fig. 3), are formed with upturned edges 14, 15, or 16, 17, at opposite sides of the same. When the said shingle 60 or shingle strip comprises a body layer 18 of waterproof felt with an asphalt coating 19 upon one side of the same and a surface layer 20 of crushed slate or the like, the upturned margins 14, 15 or 16, 17, are preferably 65 formed between dies (not shown) which firmly compress the upstanding portion of the felt layer 18, as at 21 (Fig. 5) and draw the asphalt and slate layers 19, 20, over the edge of the same, as at 22 and 23. The 70 crushed slate layer 20 and the asphalt layer 19 thus extend uniformly over the weather portion of the shingle or shingle strip, including the upturned edges of the felt layer 18. The roof surface to which the shingles 75 or shingle strips are applied is thereby covered with crushed slate in all parts and no part of the felt layer 18 is directly exposed to the weather or to falling sparks or fire brands.

It will, of course, be understood that the upturned margins 14, 15, or 16, 17 of the shingles 10 and shingle tabs 12 furnish a sufficient separation of the weather portions of adjacent shingles or shingle tabs without 80 discarding any part of the original web (not shown) from which the corresponding elements are cut and without any necessity for separating the covered portions of adjacent elements in the same row when applying 85 them to a roof. Furthermore, the upper ends of the upturned margins 14, 15, and 16, 17, provide guide shoulders against which the lower ends or edges of the elements of the next succeeding row are to be placed and 90 whether covered with the individual shingles 10 or with shingle strips 11 of any length, the finished roof has the appearance of being formed from separate elements of substantial thickness. While the shingle 10 and 100 shingle tabs 12 are shown as being formed with parallel sides, the invention is not limited to roofing elements of this shape.

I claim as my invention:

1. A prepared roofing element comprising 105 weather and covered portions of flexible laminated sheet material with an integral vertical flange comprising all the layers of the said laminated sheet material extending along one of the side edges of the said 110 weather portion.

2. A prepared roofing element comprising

ing throughout its weather and covered portions a uniform width of flexible laminated sheet material, a part of the said sheet material extending along one of the side edges 5 of the weather portion of the element and comprising all the layers of the said laminated sheet material being folded upwardly to provide a reenforcing marginal flange and to reduce the width of the element in 10 its said weather portion.

3. A prepared roofing element comprising weather and covered portions of flexible laminated sheet material with integral vertical flanges comprising all the layers of 15 the said laminated sheet material extending along each of the side edges of the said weather portion.

4. A prepared roofing element comprising throughout its weather and covered portions a uniform width of flexible laminated sheet material, a part of the said sheet material extending along each of the side edges of the weather portion of the element and comprising all the layers of the said laminated sheet material being folded upwardly 25 to provide reenforcing marginal flanges and to reduce the width of the element in its said weather portion.

5. A prepared roofing element comprising weather and covered portions of laminated structure including a body layer of sheet ma-

terial, an asphalt layer and a layer of grit, the sheet constituting the said body layer being folded upwardly along one of the side edges of the weather portion of the element to form an upstanding integral flange and the said asphalt and grit layers being extended over the upper edge of the said flange. 35

6. A prepared roofing element comprising 40 covered and weather portions, the latter being of laminated structure including a body layer of sheet material, an asphalt layer and a layer of grit, the sheet constituting the said body layer being folded upwardly 45 along one of the side edges of the weather portion of the element to form an upstanding integral flange and the said asphalt and grit layers being extended over the upper edge of the said flange. 50

7. A prepared roofing element comprising throughout its weather and covered portions, a uniform width of flexible sheet material of laminated structure comprising a body layer, a part of the said sheet material including its said body layer extending along one of the side edges of the weather portion of the element being folded upwardly to provide a vertical reenforcing marginal flange and to reduce the width of 60 the element in its said weather portion. 55
